GRINDING WHEEL TRUING APPARATUS

Carl G. Flygare and Raymond D. Ellison, Worcester, Mass., assignors to Norton Company, Worcester, Mass., a corporation of Massachusetts

Application September 8, 1950, Serial No. 183,688

2 Claims. (Cl. 125—11)

1

The invention relates to grinding machines and more particularly to a grinding wheel truing apparatus for truing a predetermined form or shape on the operative face of a grinding wheel.

One object of the invention is to provide a simple and thoroughly practical formed wheel truing apparatus for truing a predetermined form or shape on a grinding wheel. Another object is to provide a truing apparatus in which the truing tool is free to move longitudinally and transversely and governed by a master form or template to generate a predetermined contour on the operative face of a grinding wheel. Another object of the invention is to provide a manually operable truing tool support which is arranged to move longitudinally and transversely while a follower is manually maintained in operative engagement with a form or template to generate a predetermined shape on the periphery of a grinding wheel. A further object of the invention is to provide a truing apparatus having a truing tool holder which is supported for longitudinal and transverse movements relative to the grinding wheel by a plurality of anti-friction rollers to facilitate free movement of the holder to maintain a follower in operative engagement with a master form or template so as to generate a predetermined shape on the periphery of a grinding wheel. Other objects will be in part obvious or in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings in which is shown one of various possible embodiments of the mechanical features of this invention,

Fig. 1 is a plan view of the improved grinding wheel truing apparatus;

Fig. 2 is a vertical sectional view, taken approximately on the line 2—2 of Fig. 1, through one of the supporting brackets;

Fig. 3 is a fragmentary sectional view, taken approximately on the line 3—3 of Fig. 2;

Fig. 4 is a sectional view, on an enlarged scale, taken approximately on the line 4—4 of Fig. 1, showing the truing tool holder together with the supporting carriage and forming bar;

Fig. 5 is a fragmentary horizontal sectional view, taken approximately on the line 5—5 of Fig. 4;

Fig. 6 is a fragmentary horizontal sectional view, on an enlarged scale, showing the follower

2

and the truing tool swung in a counterclockwise direction;

Fig. 7 is a similar fragmentary horizontal sectional view, showing the follower and the truing tool in central positions;

Fig. 8 is a similar fragmentary horizontal sectional view, showing the follower and the truing tool swung in a clockwise direction;

Fig. 9 is a perspective view of a gage for gaging the shape of the grinding wheel after truing;

Fig. 10 is a sectional view, on an enlarged scale, taken approximately on the line 10—10 of Figs. 1 and 4;

Fig. 11 is a sectional view, on an enlarged scale, taken approximately on the line 11—11 of Figs. 1 and 4;

Fig. 12 is a sectional view on an enlarged scale, taken approximately on the line 12—12 of Figs. 1 and 11;

Fig. 13 is a fragmentary sectional view, on an enlarged scale, taken approximately on the line 13—13 of Fig. 12, through one of the anti-friction rollers for supporting the truing tool carriage;

Fig. 14 is a fragmentary sectional view, on an enlarged scale, taken approximately on the line 14—14 of Figs. 1 and 4;

Fig. 15 is a fragmentary view of apparatus for grinding the follower to a shape identical with that of the truing tool; and

Fig. 16 is a horizontal sectional view taken approximately on the line 16—16 of Fig. 15, showing the grinding wheel in section and the holder for supporting the follower and truing tool in elevation.

A grinding wheel truing apparatus has been illustrated in the drawings comprising a work table 10 which is provided with dove-tailed surfaces 11 and 12 for supporting a pair of spaced brackets 13 and 14. The brackets 13 and 14 are provided with clamping blocks 15 and 16 respectively, by means of which the brackets 13 and 14 may be clamped in adjusted position on the table 10.

The clamping arrangement for the brackets 13 and 14 is identical, consequently only one of these arrangements has been shown in detail. This clamping mechanism comprises a rod 17 which extends through a clearance hole 18 within the bracket 13. The lower end of the rod 17 is provided with a nut 19 which is screw threaded onto the end portion thereof. The other end of the rod 17 is provided with a clamping nut 20 and a spacing washer 21. In order to facilitate longi-

tudinal movement of the rod 17 to clamp and release the bracket 13 from the table 10, a hook shaped spacer 22 is pivotally supported by a stud 23 on the bracket 13. The parts as shown in Fig. 2 illustrate the bracket 13 clamped in position on the table 10. If it is desired to release the bracket to remove the truing apparatus from the table 10, the clamping nut 20 is loosened, after which the hook shaped spacer 22 is swung in a counter-clockwise direction (Fig. 3) after which the rod 17 may be moved longitudinally toward the right so that the clamping block 15 will clear the dovetailed surface 12 of the table 10 to facilitate removing the bracket 13 therefrom. The clamping mechanism for the bracket 14 is identical with that just described and comprises a longitudinally extending rod (not shown) which is provided at its upper end (Fig. 1) with a nut 25. The lower end thereof (Fig. 1) is provided with a clamping nut 26, a washer 27 and a hook-shaped spacer 28.

The brackets 13 and 14 serve as supports for a pair of spaced parallel longitudinally extending slide rods 30 and 31 which serve as a support for a longitudinally movable carriage 32. The carriage 32 is provided with clearance holes 33 and 34 through which the rods 30 and 31 respectively pass. An anti-friction bearing support for the carriage 32 is provided comprising a plurality of anti-friction rollers 35, 35a and 35b which are arranged symmetrically with respect to the clearance hole 33 and the rod 30. These rollers 35, 35a and 35b are supported by studs 36, 36a and 36b respectively. The stud 36b is provided with an eccentric portion 37 by means of which the roller 35b may be adjusted relatively toward and from the rod 30.

A similar set of rollers 40, 40a and 40b are provided on the carriage 32 spaced from the rollers 35, 35a and 35b. The rollers 40, 40a and 40b are supported by studs 41, 41a and 41b. One of the studs 41, preferably 41b, is similarly provided with an eccentric portion (not shown) identical with that shown in connection with the stud 36b to facilitate adjustment of the roller 40b. The two sets of rollers 35, 35a and 35b and 40, 40a and 40b serve as anti-friction supports for the forward end of the carriage 32 and serve to guide the carriage in a path parallel to the axis of the grinding wheel being trued.

Two pair of spaced guiding rolls 45 and 45a and 46 and 46a are arranged in spaced relationship with each other to engage the upper and lower surfaces of the rod 31 to support and steady the left hand end of the carriage 32 (Fig. 4). It will be readily apparent from the foregoing disclosure that the carriage 32 is supported by anti-friction rollers, as above described, to provide a free longitudinal movement thereof. The studs 47a and 48a are provided with eccentric portions similar to stud 36b.

A transversely movable slide bar 50 passes through a transversely extending bore 51 formed in the carriage 32. The slide bar 50 is supported by two sets of symmetrically arranged anti-friction rollers 52, 52a and 52b located adjacent to the left hand end of the slide bar 50 and rollers 53, 53a and 53b located adjacent to the right hand end thereof. The rollers 52, 52a and 52b are supported by a plurality of studs 54, 54a and 54b respectively. The rollers 53, 53a and 53b are similarly supported by a plurality of studs 55, 55a and 55b. At least one of the studs 54 and 55 is provided with an eccentric similar to that shown in connection with the stud 36b to facilitate adjusting one of the rollers to take up backlash.

between the parts so as to provide a free movement of the transversely movable slide bar 50.

A suitable mechanism is provided to prevent rotation of the slide bar 50 during this transverse movement. Portions of the slide bar 50 are cut away to form parallel guide surfaces 60 and 61 (Fig. 14). The carriage 32 is provided with a pair of rollers 62 and 63 which are supported by studs 64 and 65 respectively. One of the studs 64 or 65 is preferably provided with an eccentric portion (not shown) to facilitate adjustment for backlash between the parts. It will be readily apparent from the foregoing disclosure that the rollers 62 and 63 cooperating with the guide surfaces 60 and 61 serve to hold the slide rod 50 against rotary motion during its transverse movement.

In order to generate a predetermined shape on the operative face of the grinding wheel being trued, a forming bar or template 68 is provided which is fastened to the brackets 13 and 14 by screws 69, 69a, 69b and 69c (Fig. 1). The forming bar 68 passes through an elongated clearance slot 66 formed in the slide bar 50 and also through an elongated clearance slot 67 formed in the carriage 32 (Fig. 4).

A truing tool is adjustably supported on the right hand end of the slide bar 50 (Fig. 4). The slide bar 50 is provided with a vertically arranged stud 70 which serves as a pivotal support for a truing tool holder 71 having a truing tool 72 fixedly mounted therein. The truing tool holder 71 is provided with a plurality of conically shaped depressions 73, 74 and 75 formed on the upper face thereof. A set screw 76 carried by the slide bar 50 is provided with a conically shaped end which is arranged to engage the depressions 73, 74 and 75 to locate the truing tool holder in predetermined positions for a truing operation. When the truing tool holder is positioned as shown in Figs. 5 and 7, the set screw 76 is in engagement with the depression 74 to hold the truing tool 72 in a central position. The truing tool holder may be adjusted either in a counter-clockwise direction into the position illustrated in Fig. 6 or in a clockwise direction into the position illustrated in Fig. 8 by loosening the screw 76 and swivelling the truing tool holder 71 after which the set screw is then tightened to lock the truing tool holder in adjusted position.

In order to generate a predetermined shape on the periphery of the grinding wheel, a suitable follower mechanism is provided on the slide bar 50. The slide bar 50 is provided with a vertically extending stud 80 the lower end of which is keyed to a follower holder 81 having a follower 82 fixedly mounted thereon. The follower holder 81 is provided with a plurality of V-shaped notches 83, 84 and 85 the positions of which correspond with conically shaped depressions 73, 74 and 75 in the truing tool holder 71. The slide bar 50 is provided with a slidably mounted detent rod 86 supported within an axially extending bore 87. A compression spring 88 (Fig. 4) serves normally to maintain the V-shaped end of the detent rod 86 in engagement with one of the V-shaped notches 83, 84 or 85. An actuating knob 89 is mounted on the end of the detent rod 86 to facilitate withdrawing the detent rod to index the follower holder 81 when desired. A manually operable actuating handle 90 is arranged adjacent to the left hand end of the slide bar 50 (Fig. 4) to facilitate manual movement of the slide bar 50 to maintain the follower 82 in operative engagement with the forming bar 68. It will

be readily apparent from the foregoing disclosure that by manipulation of the handle 90, the slide bar 50 may be moved transversely and the carriage 32 moved longitudinally as permitted by the shape of the forming bar 68 to transmit a pre-determined controlled movement to the truing tool 72 so as to duplicate the shape of the master template or forming bar 68 on the operative face of a grinding wheel 92. The stud 80 is provided with an actuating arm 91 to facilitate positioning of the follower holder 81 to correspond with the position of the truing tool holder 71.

As shown in the drawing, the forming bar 68 is shaped to true the operative face of the grinding wheel 92 having two cylindrical portions 92a and 92c, a tapered portion 92b, and a radius 92d. The cylindrical portions 92a and 92c of the grinding wheel 92 are preferably trued with the truing tool holder 71 located in a central position, that is with the set screw 76 in engagement with the conically shaped depression 74 as shown in Figs. 5 and 7. While truing these portions of the grinding wheel, the follower holder 81 is located in a central position with the pawl rod 86 in engagement with the V-shaped notch 84. For truing a tapered portion on the wheel such as surface 92b, the truing tool holder 71 is swung in a counter-clockwise direction into the position illustrated in Fig. 6 with the set screw 76 in engagement with the conically shaped depression 73. During this truing operation, the follower holder 81 is also swivelled in a counter-clockwise direction so that the pawl rod 86 engages the notch 83. Similarly when it is desired to true a radius portion such as 92d, the truing tool holder 71 is swung in a clockwise direction into the position illustrated in Fig. 8 with the set screw 76 engaging the conically shaped depression 75. During this truing operation, the follower holder 81 is also swivelled in a clockwise direction so that the detent rod 86 engages the V-shaped notch 85 to locate the follower 82 in a position to correspond with the truing tool 72.

In order that the follower 82 may transmit an exact corresponding movement to the truing tool 12 in corresponding positions thereof, it is essential that the follower 82 be shaped identical with the shape of the truing tool 12. This is preferably accomplished by setting up the truing tool holder 71 and the follower holder 81 and utilizing the truing tool 12 as a master form to generate an identical shape on the follower 82. This is preferably accomplished by apparatus such as shown in Figs. 15 and 16. A grinding apparatus is provided having a table 100 having an upper plane surface 101. A rotatably mounted grinding wheel 102 is provided having a plane operative face 103. An angle iron 104 is clamped on the table 100 by means of a clamping bolt 105, the head of which is slidably mounted within a T-slot 106 formed in the table 100. The angle iron 104 is provided with a vertically arranged plane face 107 which is adjusted into alignment with the plane operative face 103 of the grinding wheel 102. A holder 108 is slidably mounted on the upper surface 101 of the table 100. The holder 108 is provided with a horizontally extending boss 109 which supports a vertically arranged spindle 110. The truing tool holder 71 is arranged to be keyed onto the lower end of the spindle 110 and locked thereon by means of a clamping nut 111. The follower holder 81 is arranged to be slidably keyed to the upper end of the spindle 110 and may be clamped thereon by a clamping nut 112 (Fig. 15). The key ways

formed in the truing tool holder 71 and the follower holder 81 are arranged so that the truing tool 72 and the follower 82 are vertically aligned when mounted on the spindle 110. It will be readily apparent from the foregoing disclosure that by sliding the holder 108 on the plane surface 101 and maintaining the truing tool 72 in engagement with the surface 107 of the angle iron 104, the follower 82 will be ground to the same identical shape as the truing tool 72. After this shaping operation has been performed, the truing tool holder 71 and the follower holder 81 may again be mounted in position on the slide bar 50 for a truing operation.

15 It will be readily apparent from the foregoing disclosure that due to the construction of this truing apparatus, it is merely necessary for the operator to manipulate the handle 90 so as to maintain the follower 82 in operative engagement
20 with the forming bar 68 during the transverse movement of the slide bar 50 and the longitudinal movement of the carriage 32 to generate an identical form on the periphery of the grinding wheel 92.

25 The operation of the improved truing apparatus will be readily apparent from the foregoing disclosure. A forming bar 68 having the desired form of equal dimensions that is to be reproduced on the grinding wheel 92 is inserted in position and fastened to the brackets 13 and 14 by the screws 69, 69a, 69b and 69c. The brackets 13 and 14 may then be adjusted longitudinally on the table 10 to position the shape on the forming bar 68 opposite and in alignment with the operative face of the grinding wheel 92. If desired, this positioning movement may be accomplished by a conventional traversing adjustment of the table 10. After the truing apparatus is in the desired position, the clamping nuts 20 and 26 are tightened to lock the brackets 13 and 14 in adjusted position relative to the table 10. The handle 90 may then be moved toward the right (Fig. 4) to move the follower 82 into operative engagement with the face of the forming bar 68, after which the grinding wheel may be advanced toward the truing tool 72 by an amount equal to that desired to be trued therefrom. By manipulation of the manually operable handle 90, the slide bar 50 may be moved transversely and the carriage 32 moved longitudinally while maintaining the follower 82 in operative engagement with the forming bar 68 to traverse the truing tool 72 through a predetermined path to true the operative face of the grinding wheel. If desired, the entire traversing movement may be made with the truing tool 72 in a central position, or, if desired, due to the nature of the shape being reproduced, the truing tool holder 71 may be swivelled in a manner above described to position the truing tool 72 for the truing operation.

60 It will thus be seen that there has been provided by this invention apparatus in which the objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings 65 is to be interpreted as illustrative and not in a limiting sense.

We claim:

1. In a grinding wheel truing apparatus having a frame, a longitudinally movable carriage, and anti-friction rollers on said carriage to support

the carriage, a transversely movable cylindrically-shaped slide bar on said carriage, anti-friction rollers on said carriage to support said slide bar, a truing tool holder pivotally mounted on one end of said slide bar, a truing tool thereon, a plurality of spaced index depressions in the upper surface of said truing tool holder, a set screw on said slide bar engageable with one of said depressions to facilitate indexing the truing tool into one of a plurality of predetermined positions, a follower pivotally mounted on said slide bar in alignment with said truing tool, a plurality of spaced V-shaped notches formed on said follower holder, said notches being spaced to correspond with the spacing of the depressions on the truing tool holder, a V-shaped detent slidably mounted on said slide bar for engaging one of the said notches to facilitate positioning the follower precisely in correspondence with the truing tool holder, said follower being shaped identical with said truing tool, a forming bar on said frame having a shape identical with that to be trued on a grinding wheel, and manually operable means on said slide bar to facilitate moving said slide bar transversely and said carriage longitudinally to maintain the follower in operative engagement with said forming bar so as to true a predetermined shape on the operative face of a grinding wheel.

2. In a grinding wheel truing apparatus having a pair of spaced supporting brackets, a pair of parallel spaced slide rods thereon, a longitudinally movable carriage slidably supported on said rods, anti-friction rollers between said carriage and said rods, a transversely movable slide bar on said carriage, anti-friction rollers between said slide bar and said carriage, a truing tool holder pivotally mounted on said slide bar, a truing tool thereon, a plurality of spaced index depressions in the upper surface of said truing tool holder, a set screw on said slide bar to engage one of said depressions to facilitate locating the

truing tool in one of a plurality of positions, a forming bar supported by said brackets having a shape identical with the shape to be trued on a grinding wheel, a follower holder pivotally supported on said slide bar, a follower on said holder which is shaped identically with the truing tool and arranged in axial alignment with the truing tool, a plurality of spaced V-shaped index notches formed on the follower holder, said notches being spaced to correspond with the spacing of the depression on the truing tool holder, a spring pressed V-shaped detent slidably mounted on said slide bar which is maintained in engagement with one of the notches on the follower holder to facilitate positioning the follower precisely in correspondence with the truing tool holder, and a manually operable handle on said slide bar to facilitate a transverse movement of the slide bar and a longitudinal movement of the carriage to maintain the follower in operative engagement with the forming bar so that the truing tool is moved through a path identical with the shape on the forming bar to true an identical shape on a grinding wheel.
